UNITED STATES PATENT OFFICE

2,148,330

AUTOMATIC DRAIN FLOAT

John J. Tokheim, Cedar Rapids, Iowa.

Application June 19, 1937; Serial No. 149,214.

2 Claims. (Cl. 137—104).

This invention relates to floats for use in liquid storage tanks, steam boilers and the like to rise and fall with changes in the level of the liquid therein and to actuate a liquid level indicator or a liquid supply control valve or, in fact, to actuate any means to be operated responsive to rise or fall of liquid in a tank, boiler or the like, and has particular reference to a float for use in either high pressure or sub-atmospheric pressure liquid tanks or boilers which may or may not be subjected to temperature changes.

For a float to be accurate in operation it is necessary that its buoyancy remain constant, and in order to maintain its buoyancy constant it is necessary that it be subjected to the same pressure interiorly as exteriorly, which means that it cannot be completely closed or sealed, but must have an opening for equalization of pressure between its interior and its exterior. If, however, a float is provided with an opening for equalization of pressure between its interior and its exterior, and if it is used in a steam chamber or a tank containing vapors, condensation of the steam or vapors results in liquid collecting in the float with consequent change in its buoyancy and impairment of its accuracy, unless the condensate is substantially constantly evacuated therefrom.

Accordingly, the general object of the present invention is to provide a float having an opening for equalization of pressure between its interior and its exterior and which includes means, operable responsive to changes in pressure between its interior and its exterior, to effect evacuation of condensate therefrom, whereby it is maintained substantially free of condensate and of substantially constant buoyancy.

In order that the present float may not corrode or deteriorate it preferably is formed from glass, and in this connection a special object of the invention is to provide novel means for the connection therewith in a firm, strong manner not only the means for evacuating the same of condensate, but also a liquid level indicating tape, a liquid supply control valve or whatever other device is to be actuated by the float.

With the foregoing and other objects in view, which will become more fully apparent as the nature of the invention is better understood, the same consists in the novel features of construction, combination and arrangement of parts as will be hereinafter more fully described, illustrated in the accompanying drawing and defined in the appended claims.

In the accompanying drawing:

Fig. 1 is a vertical section through a float con-

structed in accordance with one practical embodiment of the invention; and

Fig. 2 is a section at right angles to Fig. 1.

Referring to the drawing in detail, 10 designates the present float body which, of course, is hollow and which may be formed from any suitable material into any desired size and shape, although, as aforesaid, it preferably is formed from glass and preferably is of flattened spherical shape as shown. Also, as shown, the body 10 is completely closed except for a top opening therein of relatively large size designated as 11.

Covering the opening 11 is a preferably metallic cap 12 which marginally seats upon a gasket 13 disposed upon the upper face of the top wall of the body 10 in surrounding relationship to said opening 11 and which may be drawn air-tightly against said gasket in any desired manner. As illustrated in the present instance, a bar 14 is disposed interiorly of the body 10 in spanning relationship to the opening 11 and is seated at its ends against the under face of the top wall of said body 10 and at its under side has seated thereagainst a nut 15 in which is threaded the lower end of a bolt 16 which passes loosely through an opening in the cap 12. Accordingly, by tightening the bolt 16 the cap 12 is drawn into air-tight engagement with the body 10 and a strong connection is effected between said cap and said body so that there is an equally strong connection between said body and any means to be actuated by the same which may be connected therewith through said cap and its securing means.

The bar 14 preferably is provided with depending side flanges 17 or equivalent means for cooperation with the nut 15 to hold the same against rotation, and the bolt 16, directly below its head 18, preferably is downwardly tapered as indicated at 19, for cooperation with a correspondingly tapered top portion of the opening in the cap 12 through which said bolt extends, to provide an air-tight seat around said bolt when the latter is tightened.

The means to be actuated by the body 10 may be connected with the securing means for the cap 12 in any suitable manner. As illustrated in the present instance, the said means to be actuated by said body 10 comprises a liquid level indicating tape 20 having its lower end portion clamped between the ends of a metal yoke 21 the intermediate portion of which is clamped between the head of the bolt 16 and the top face of the cap 12.

A small tube 22 is threaded at its upper end

into the cap 12, or otherwise is suitably connected at its upper end with said cap, and extends downwardly from said cap through the opening 11 into the body 10 and has its lower end spaced from, but disposed closely adjacent to, the bottom of the body 10. At its upper end said tube 22 is in communication with an inner end portion of a small horizontal opening 23 which is formed in the cap 12 and which opens through one side thereof. Thus, provision is made for equalization of pressure between the interior and the exterior of the body 10 so that regardless of variations in pressure exteriorly of said body 10, the buoyancy of said body will remain constant inssofar as concerns variations in pressure exteriorly of said body. At the same time, provision is made for evacuating the body 10 of substantially all condensate which may collect therein, for the collection of only a small amount of condensate within the body 10 will suffice to cover the lower end of the tube 22 and when this condition exists any slight drop in pressure exteriorly of the body 10 will result in the higher pressure within said body forcing the condensate from said body through the tube 22 and the opening 23. In this connection it is apparent that, due to the horizontal disposition of the opening 23, condensate or other matter is prevented from gravitating directly downwardly into the tube 21.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

1. A float comprising a hollow glass body having a top opening, a cap covering said opening and seated on the top of said body, a bar within said body spanning said opening and seated against the under side of the top of said body, means extending between said bar and said cap for clamping said cap to said body, means to be actuated by said body connected therewith by said first mentioned means, and a tube carried by said cap and depending therefrom to a point closely adjacent to the bottom of said body and providing communication between the interior and the exterior of said body.

2. A float as set forth in claim 1 including means protectively covering the upper end of the vent tube to prevent direct downward flow of moisture into said tube.

JOHN J. TOKHEIM.
